(57) **CLAIM**

The ornamental design for electric bicycle frame as shown and described.

DESCRIPTION

1. Electric bicycle frame

1.1 : Front

1.2 : Left

1.3 : Right

1.4 : Top

1.5 : Bottom

1.6 : Perspective

1.7 : Cross sectional

1.8 : Cross sectional

1.9 : Cross sectional

1.10 : Cross sectional

Fig. 1.1 is a front view of an electric bicycle frame embodying our new design, the letters and direction of "A-A" correspond to the cross-sectional reference view of Fig. 1.7, the letters and direction of "B-B" correspond to the cross-sectional reference view of Fig. 1.8, the letters and direction of "C-C" correspond to the cross-sectional reference view of Fig. 1.9, the letters and direction of "D-D" correspond to the cross-sectional reference view of Fig. 1.10; Fig. 1.2 is a left view thereof; Fig. 1.3 is a right view thereof; Fig. 1.4 is a top view thereof; Fig. 1.5 is a bottom view thereof; Fig. 1.6 is a perspective view thereof; Fig. 1.7 is a cross-sectional view A-A thereof; Fig. 1.8 is a cross-sectional view B-B thereof; Fig. 1.9 is a cross-sectional view C-C thereof; Fig. 1.10 is a cross sectional view D-D thereof.

1 Claim, 10 Drawing Sheets
